SHOE

Sol J. Waxelbaum, Atlanta, Ga.

Application January 6, 1936, Serial No. 57,686

6 Claims. (Cl. 36—45)

This invention relates to shoes, particularly to ladies' shoes. It has for its principal objects to provide the shoe upper with relatively movable sections adapted to overcome the tendency for the portion of the upper at the front end of the foot opening to chafe the foot, to minimize wrinkling of the upper between the toe and the front part of the foot opening when the foot is bent, to reduce the tendency of the foot opening of a pump to gap when the foot is bent, to permit elongation of the foot opening to accommodate high arches, and to provide for simplicity and cheapness of construction. The invention consists in making the shoe upper in sections that are connected along their adjacent margins by a joint adapted to permit relative movement of the sections in all directions; and it also consists in the parts and in the arrangements and combinations of parts hereinafter described and claimed.

In the accompanying drawings, which form part of this specification and wherein like symbols refer to like parts wherever they occur,

Fig. 1 is a perspective view of a pump embodying my invention,

Fig. 2 is a plan view of a portion of the forepart of said pump,

Fig. 3 is an enlarged cross-section through the joint between the sections of the upper on the line 3—3 in Fig. 2,

Fig. 4 is a similar cross-section on the line 4—4 of Fig. 2,

Fig. 5 is a fragmentary cross-section through the upper at one end of the joint, the section being taken on the line 5—5 of Fig. 1,

Fig. 6 is a perspective view of a pump of modified form,

Fig. 7 is an enlarged fragmentary plan view of the forepart of the pump shown in Fig. 6,

Fig. 8 is a perspective view of a one-strap shoe embodying my invention,

Fig. 9 is an enlarged fragmentary side elevation of the buckle side of the one-strap shoe shown in Fig. 8,

Fig. 10 is a perspective view of an Oxford shoe embodying my invention; and

Fig. 11 is a fragmentary plan view of the shoe in Fig. 10 in the region of the front of the foot opening.

In Figs. 1 to 5, inclusive, my invention is shown in connection with a pump having an upper comprising a section A provided with a foot opening B, a vamp or forward section C, and hinge slip joint D connecting said sections together along a line extending around the front

or throat of said foot opening and downwardly and rearwardly on each side of the pump to points adjacent to the shank portion of the pump. Said hinge slip joint preferably comprises a series of tabs 1 that are spaced apart longitudinally of the front edge of the section A of the upper and a similar series of tabs 2 that are spaced apart longitudinally of the upper edge of the vamp or forward section C of said upper. The tabs of one section of the upper extend into the spaces between the tabs of the other section thereof; and the tabs 1 and 2 of the respective sections are doubled back to form loop openings 3 and 4 therein. The tabs of the two sections are loosely secured together by means of a cord 5, which extends through the loops 3 in the tabs and has its ends sewed or otherwise anchored, as at 6, between vamp section C of the upper and a lining C' therefor.

By the arrangement described, the hinge slip joint between the two sections of the upper permits relative movement at the joint between said section in all directions, thereby overcoming the tendency for the upper to gap on opposite sides of the foot opening and to wrinkle between the toe and foot opening when the foot is bent and presses forwardly against the throat portion of said foot opening. Under such conditions, the pressure of the foot against the throat of the foot opening causes the tabs 1 around said throat to slide forward in the spaces between the tabs 2 of the forward section of the pump and thus relieve said section of the pressure that causes it to wrinkle and to spread sidewise. This forward movement of the tab 1 also prevents chafing of the foot by the edges of the upper at the throat of the foot opening; and it also permits said opening to elongate slightly and accommodate itself to a foot having a high arch.

In the construction shown in Figs. 6 and 7, the invention is shown embodied in a seamless pump whose upper has a collar 7 inserted therein that forms the front end or throat of the foot opening in said upper. The collar 7 and the vamp portion of the upper are connected together along their adjacent margins by a joint D' similar to the joint D shown in Figs. 1 to 5, inclusive. The joint D' comprises looped tabs 1a that are spaced apart along the margin of the collar 7 and extend into the spaces between similar looped tabs 2a that are spaced apart longitudinally of the adjacent margins of the main body portion of the upper; and the cooperating tabs of the two sections are secured together by a flexible cord 5a which extends through the

loops thereof and has its ends anchored in said main body portion of said upper.

- 5 In the modification shown in Figs. 8 and 9, the invention is shown embodied in a one-strap shoe, wherein the front or throat portion of the foot opening in the upper is formed by a collar 8 that extends upwardly on opposite sides of said opening to points opposite the strap portion 9 of said shoe. One end of the vamp collar 8 has the strap 10 buckle 10 secured thereto; and the adjacent margins of the collar and upper are secured together by a joint D'' comprising longitudinally spaced loops 1b along the margin of the collar 8 that extend into the spaces between a similar series 15 of longitudinally spaced loops 2b along the margin of the upper, the series of loops being connected by a flexible cord 5b, which passes therethrough and has its ends suitably anchored to the upper.
- 20 In the modification shown in Figs. 10 and 11, an Oxford shoe has an eyelet stay 11 which is secured to the shoe upper by a joint D''' similar to the joints hereinbefore described. The joint D''' comprises a series of loops 1c spaced apart 25 longitudinally of the margin of the eyelet stay 11 that extend into spaces between a similar series of loops 2c that are spaced apart along the adjacent margin of the upper, the two series of loops being connected by a flexible cord 5c, 30 which extends therethrough and has its ends suitably anchored in the upper on opposite sides of the foot opening.

Obviously, the hereinbefore described construction admits of considerable modification 35 without departing from the invention. Therefore, I do not wish to be limited to the types of shoes or to the location of the hinge slip joint shown and described.

What I claim is:

- 40 1. A shoe having a vamp comprising toe and throat sections that are connected together along their adjacent margins by a hinge slip joint adapted to permit forward bodily movement of said throat section independently of said toe 45 section when the foot presses forwardly against said throat section.
2. A shoe having a vamp comprising toe and throat sections that are connected together along their adjacent margins by a joint comprising series of loops spaced apart along the adjacent 50 margins of the respective sections, the loops of one section extending loosely into the spaces be-

tween the loops of the other section and normally spaced from the bottoms of said spaces, and a flexible member extending loosely through the loops of both sections with its ends anchored to one of said sections.

3. A shoe having an upper comprising two sections connected together around in front of and adjacent to the foot opening in said upper by a hinge slip joint adapted to permit forward bodily movement of the foot opening section independently of the other section.

4. A shoe having an upper comprising two sections connected together around the front of the foot opening in said upper just rearwardly of the toe covering portion thereof by a joint comprising loops spaced apart along the adjacent margins of the respective sections, the loops of one section being disposed between the loops of the other section, and a flexible member passing loosely through the loops of both sections with its ends anchored to one of said sections, the loop of one section being normally spaced from the sides and bottoms of the spaces between the loops of the other section.

5. A pump having an upper provided with a 25 foot opening, a collar section forming the front end or throat of said foot opening, and a joint connecting said collar section to the portion of said upper located forwardly thereof, said joint comprising series of loops spaced apart along the 30 adjacent margins of said upper and said collar section, the loops along one of said margins extending into the spaces between the loops along the other of said margins and spaced from the sides and bottoms of said spaces, and a cord 35 loosely connecting the loops of said upper and said section together, the ends of said cord being anchored to said upper.

6. A shoe having an upper comprising a main section and an eyelet section connected together 40 rearwardly of the toe covering portion of said upper by a joint comprising loops spaced apart along the adjacent margins of the respective sections, the loops of one section being disposed between the loops of the other section and spaced 45 from the bottoms and sides of the spaces between the loops of said last mentioned section, and a cord passing loosely through the loops of both sections with its ends anchored to said main section.

SOL J. WAXELBAUM.
